UNITED STATES PATENT OFFICE

HENRY FRANK BEEMAN, OF FORT COLLINS, COLORADO

GAS-SAVING ATTACHMENT FOR INTERNAL-COMBUSTION ENGINES

Application filed September 27, 1928. Serial No. 308,868.

This invention relates to a gas saving attachment for internal combustion engines and is designed primarily for use in connection with automobile engines.

5 One of the objects of the invention is to provide a simple and efficient device which can be combined readily with the engine and, when in position, will supply vapor from the overflow pipe of the engine radiator to the 10 intake manifold, means being employed whereby this vapor is washed before entering the manifold and is mixed thoroughly with a heavy oil which, when carried into the engine, will act to increase the smoothness of 15 operation of the engine.

A further object is to provide simple means for washing the vapor so as to prevent the particles of dust from being carried into the engine and injuring the same.

20 A further object is to supply water vapor to the intake manifold, thereby permitting a considerable reduction in the amount of gas used and also practically eliminating carbon deposits.

25 With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

30 In the accompanying drawings, the preferred form of the invention has been shown.

In said drawings,

Figure 1 is view partly in elevation and partly in section of a portion of an automobile engine having the present improvements combined therewith.

Figure 2 is a perspective view showing one way in which the intake pipe of the attachment can be connected to the overflow pipe 45 of the radiator.

Referring to the figures by characters of reference A designates a portion of the intake manifold of an automobile engine and B designates a portion of the radiator provided 50 with the usual overflow pipe C.

The attachment constituting the present invention includes a tubular body 1 preferably formed of thick glass the ends of which are seated in grooves 2 formed in heads 3 and 4. These heads are drawn toward each other 55 by tie rods 5 and, by first placing gaskets 6 upon the ends of the tubular body 1, the tightening of the rods 5 will result in the formation of a shield chamber 7. Opening through the upper head 3 of the attachment is a nipple 8 to which is connected an outlet tube 9 which can be of copper or other material easily bent. Another tube 10 is suspended within the chamber 7 from the head 3, the upper end of this tube being coupled as at 11 to a vapor supply tube 12 likewise preferably formed of copper or other material easily bent. An air inlet tube 13 depends from the head 3 and has a check valve 14 normally closing the upper or outer end thereof. The 70 lower end of this tube 13 is located at a considerable distance above the lower end of the tube 10 and mounted to slide within the air tube 13 is a rod 15 projecting upwardly from a float 16. This rod is so proportioned that when the float 16 rises to a point close to the lower end of the tube 13, said rod 15 will come against and unseat the check valve 14, thereby permitting air to enter the chamber 7 through the tube 13. Normally, however, 75 this valve is in closed position.

When it is desired to use the device constituting the present invention a small opening 17 is drilled into the overflow pipe C and an elongated opening 18 is cut into the tube 12 80 near its free end. A screw plug 19 which is coupled in any suitable manner to one end of the tube 9 is screwed into an opening 20 drilled in the wall of the intake manifold A. The opening 18 in tube 12 is placed where it will communicate with the aperture 17 and thereafter said tube 12 is fastened securely to the overflow tube C in any suitable manner. For example strong insulating tape indicated 85 generally at 21 can be wrapped about the engaging portions of the tubes 12 and C so as to hold them together firmly, close the free end of the tube 12 and prevent leakage of air into the tube 12. With the parts thus assembled and the body 1 and heads 3 and 4 mount 90 95 100

ed in any preferred manner adjacent the engine, the attachment is ready for use. It is first necessary to pour a mixture of heavy oil into the chamber 7. This mixture is preferably made up of one part coal-oil and two parts castor oil. A sufficient amount of the mixed oil is used to submerge the lower end of the tube 10. While the engine is in use a suction will be set up from the chamber 7 10 through the tube 9 to the intake manifold A and as the check valve 14 is normally closed, this suction will result in the withdrawal of an amount of vapor from the top of the radiator B through the upper portion of the over- 15 flow pipe C, the apertures 17 and 18 to the tube 12 and thence into the bottom portion of chamber 7. Here the vapor will rise through the oil at which time any dust or other objectionable particles commingled therewith 20 will be precipitated while the pure vapor will be free to flow into the tube 9.

Should there be an undesirable accumulation of water due to the condensation of vapor in the chamber 7, the float 16 would 25 rise sufficiently to lift rod 15 and valve 14 and thus admit air into the chamber 7 so that the operation will continue without causing the chamber to become flooded to an objectionable extent by the water. Air thus admitted will also prevent the structure from 30 overheating.

It will be understood that the pipe or tube 13 acts as a guide for the rod 15.

What is claimed is:

35 1. A gas saving attachment for internal combustion engines including a tubular body, heads clamped thereagainst and cooperating therewith to provide a chamber for holding a heavy oil, a vapor supply tube opening 40 downwardly into said chamber below the level of the oil, means for coupling said tube to the overflow tube of a radiator to receive vapor therefrom, a vapor outlet pipe extending from the upper end of the chamber and 45 means for coupling the same to the intake manifold of an engine, an air intake tube opening downwardly into the chamber, and float controlled means within the chamber for controlling the admission of air into said 50 chamber.

2. A gas saving attachment for internal combustion engines including a chamber for holding a heavy oil, a vapor supply tube opening downwardly into the contents of the chamber below the level thereof, means for connecting said tube to the overflow tube of a radiator to receive vapor therefrom, a pipe suspended within the chamber above the level 55 of the contents thereof, a check valve normally closing the outer end of said pipe, a float in said chamber, means actuated by the float for unseating the check valve when the contents of the chamber reach a predetermined 60 level, and means for maintaining communica- 65

tion between the upper portion of said chamber and the intake manifold of an engine.

In testimony that I claim the foregoing as my own, I have hereto affixed my signature.

HENRY FRANK BEEMAN.
